UNITED STATES PATENT OFFICE.

ELEK LOUIS, OF NEW YORK, N. Y.; FANNY LOUIS BEING ADMINISTRATRIX OF SAID
ELEK LOUIS, DECEASED.

COMBINATION ORGAN-STOP ACTION.

1,416,367.

Specification of Letters Patent.

Patented May 16, 1922.

Application filed June 11, 1919. Serial No. 303,347.

To all whom it may concern:

Be it known that I, ELEK LOUIS, a citizen of Hungary, and a resident of New York, in the county of New York and State of New York, have invented certain new and useful Improvements in Combination Organ Stop Actions, of which the following is a specification.

The present invention relates to electrically operated organs, and has for its main object to provide a stop mechanism, which is simple in construction, and efficient in operation.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

Figure 1 is a side elevation, partly in section, of a portion of an organ, including a stop mechanism constructed in accordance with the present invention; Fig. 2 is a section taken on line 2—2 of Fig. 1; Fig. 2^a is a section taken on line 2^a—2^a of Fig. 1; Fig. 3 is a vertical section taken through the wind-chest of the organ, showing one of its pipes; Fig. 4 is a rear elevation of one of the valves controlling the communication between the wind-chest and organ pipes; Fig. 5 is a perspective view of a rocker, forming part of the stop mechanism; and Fig. 6 is a diagram of the electric circuits of the device.

In the drawings, the numeral 10 indicates a frame or support, on which is slidably disposed a stop handle 11, the inner end of which is pivoted at 12 to one end of a lever 13. This lever is fulcrumed at 14, intermediate its ends, to the frame, and is connected by a rod 15 with a horizontally disposed stop-bar 16, the front end of which is pivoted at 17 to a link 18, the latter being fulcrumed at 19 to the organ frame.

To the rear end of the bar 16 is pivoted at 20 a contact lever 21, fulcrumed at 22 to the frame and carrying a contact piece 23, which is adapted to bridge the gap between two stationary contact points 24 of an electric circuit 25, into which is inserted a mechanism for actuating a slide or valve. This mechanism is not shown in the drawings as it is well-known and does not form part of the present invention.

The stop-bar is provided with a longitudinal slot 26, within which is disposed a rocker 27, shown in detail in Fig. 5 of the drawings. The rocker is pivoted at 28 to the bar, and comprises a flat body including two angularly disposed portions 29 and 30, arranged in such a manner that, when either one of these portions is wholly disposed within the slot, the other projects below the underface of the stop-bar 16. A lug 31 projects centrally above the upper edge of the rocker and has fixedly attached thereto a weight 32, serving to hold the rocker firmly in either one of its positions. The rocker is furthermore provided with an aperture 33, through which extends a pin 34, carried by the stop-bar, said pin serving to limit the movement of the rocker in either direction.

For setting the rocker, for a purpose hereinafter to be described, there is provided a setting-bar 35, said bar being disposed in operative relation to the said rocker below the same. This bar is fixed to a lever 36, that is fulcrumed, intermediate its ends, at 37 to the organ frame and is connected by a rigid wire 38 with a lever 39, the latter being fulcrumed at 40 to the frame. To the free end of this lever is fixed an electro-magnet 41, actuating an armature 42, that is carried by an arm 43. This arm is pivoted at its upper end to the lever 39 and provided at its lower end with a forwardly extending lug 44. Immediately above this lug is disposed one end of a bar 45, that is fulcrumed at 46 to the organ frame and carries at its other end an armature 47, actuated by an electro-magnet 48. A spring 49, bearing against the setting-bar 35, has a tendency to keep the latter in its lower position.

For the purpose of shifting the sliding stop-bar 16 from its "off" position to its "on" position, and vice versa, there are two fans 50 and 51, pivoted at 52 and 53, re-

spectively, to the frame below the said sliding bar in operative relation to the rocker 27. These fans are each provided adjacent their respective pivots with a lug 54, extending toward each other and pivoted to a downwardly projecting rigid wire 55, that is fixed to a lever 56. This last-mentioned lever extends horizontally in parallel relation to the lever 39, and is provided with a depending rigid wire piece 57 carrying adjacent its upper end an armature 58. This armature is actuated by an electro-magnet 59 on the lever 56, while the lower end of said wire piece 57 is provided with an inwardly bent lug 60, in proximity to which is disposed the free end of the bar 45 above referred to. Springs 50' are interposed between the fans 50 and 51.

The electro-magnet 41 is inserted into an electric circuit 61, and the electro-magnet 59 into an electric circuit 62. Both of these circuits contain the electromagnet 48 and a source of electric energy 63, common to both circuits. The circuit 61 is controlled by a switch 64 and the circuit 62 by a switch 65, the arrangement being such that, when the circuit 61 is closed, the electro-magnets 41 and 48 are energized, and, when the circuit 62 is closed, the electro-magnets 59 and 48 are energized.

The switches 64 and 65 are located below the keyboard 66 of the organ. Each key 67 on this board carries an electric conductor 68, that acts as a switch, overlapping the gap between contact points 69 of an electric circuit 70, into which is inserted an electro-magnet 71. The armature 72 of this electro-magnet is carried by a stem 73, that is pivoted to the wall of the wind-chest 74 of the organ. This stem is provided at its free end with a disk valve 75, controlling the communication between the interior of the wind-chest and the respective organ pipe 76.

The operation of this device is as follows:—In Fig. 1 of the drawings the stop bar 16 is in its “off” position and the portion 29 of the rocker projects below the underface of the stop bar 16. If it is intended to shift the stop bar to its “on” position, in which the contact piece 23 bridges the gap between the contact points 24, the electric circuit 62 must be closed. When this circuit is closed by operating the switch 65, the electro-magnets 59 and 48 are energized. As the magnet 59 is energized, it attracts the armature 58, thereby swinging the wire piece 57 so that its lug 60 is brought into the path of the bar 45, the latter being caused to swing around its fulcrum 46 in the direction of the arrow shown in Fig. 2 of the drawings, when the armature 47 is attracted by the electro-magnet 48. When the bar 45 swings in the direction indicated, it causes the lever 56 to move downwards

around its pivot, exerting a pull on the rigid wire piece 55, which causes the fans 50 and 51 to swing around their pivots toward each other. The fan 50, abutting against the portion 29 of the rocker, shifts, due to the movement mentioned, the stop-bar 16 in the direction of the arrow shown in Fig. 1 of the drawings, imparting a corresponding motion to the contact-lever 21, whereby the gap between the stationary contact points 24 is bridged.

As soon as the electric circuit is opened, the wire piece 57 swings back to its normal position, the springs 50' causing the other elements associated with the said wire piece 57 to move to the normal position, shown in Fig. 1 of the drawings.

If it is desired to shift the stop-bar from its “on” position to its “off” position, and the portion 29 of the rocker projects below the underface of the stop-bar, first the said rocker must be swung around its pivot so that its portion 30 projects below the stop-bar. This is accomplished by closing the electric circuit 61, whereby the electro-magnets 41 and 48 are energized. By this operation, the wire piece 38 moves with the lever 39 and causes the setting-bar 35 to move upwards, whereby the rocker is swung around its pivot point 28, so that the portion 30 thereof projects below the underface of the stop-bar. The electric circuit 61 is then opened, the spring 49 returning the elements to their normal positions. When now the electric circuit 62 is closed, the fan 51 moves the stop bar in the direction opposite to the arrow shown in Fig. 1 of the drawings.

What I claim is:—

1. In a combination organ stop-action, the combination with a horizontally disposed shiftable stop-bar, of a rocker pivotally mounted on said bar having two distinct portions extending at an angle to each other, either one of said portions being adapted to project below the underface of said bar when the other is above said underface, a shiftable bar for setting said rocker, two fans connected to move in opposite direction to engage either portion of said rocker for shifting said stop-bar endwise, two horizontally extending levers, one of said levers being connected with said setting-bar and the other one with said fans, electro-magnets, one carried by the free end of each of said levers, said magnets being in branch circuits, a downwardly extending bar upon each of said levers provided with an armature in operative relation to the respective electro-magnet, said downwardly extending bars being each provided with a lug, a bar having one of its ends in operative relation to said lugs, an armature carried by the other end of said last-mentioned bar, and an electro-magnet actuating said last-mentioned armature, said last-mentioned electro-mag-

net being in a circuit adapted to be closed simultaneously with either one of said branch circuits.

2. In a combination organ stop-action, the combination with a horizontally disposed shiftable stop-bar, of a rocker pivotally mounted on said bar having two distinct portions extending at an angle to each other, either one of said portions being adapted to 10 project below the underface of said bar when the other one is above said underface, a shiftable bar for setting said rocker, two fans connected to move in opposite directions to engage either portion of said rocker 15 for shifting said stop-bar endwise, two horizontally extending levers, one of said levers being connected with said setting-bar and the other one with said fans, electro-

magnets, one carried by the free end of each of said levers, said magnets being in branch 20 circuits, a downwardly extending bar upon each of said levers provided with an armature in operative relation to the respective electro-magnet, said downwardly extending bars being each provided with a lug, a bar 25 having one of its ends in operative relation to said lugs, an armature carried by the other end of said last-mentioned bar, and an electro-magnet actuating said last-mentioned armature, said last-mentioned electro-magnet 30 being included in the common part of said branch circuits.

Signed at New York, in the county of New York and State of New York, this 7th day of June, A. D. 1919.

ELEK LOUIS.
